UNITED STATES PATENT OFFICE.

FRANK L. PLATT, GEORGE N. HEIN, AND ROBERT R. IMPEY, OF SAN FRANCISCO,
CALIFORNIA.

HYPODERMIC-SYRINGE NEEDLE AND BASE.

1,318,586.

Specification of Letters Patent.

Patented Oct. 14, 1919.

Application filed May 6, 1919. Serial No. 295,072.

To all whom it may concern:

Be it known that we, FRANK L. PLATT, GEORGE N. HEIN, and ROBERT R. IMPEY, citizens of the United States, residing at the 5 city and county of San Francisco and State of California, have invented certain new and useful Improvements in Hypodermic-Syringe Needles and Bases, of which the following is a specification.

10 The present invention relates to improvements in needles and needle mountings for hypodermic syringes.

The principal objects of our present invention are to provide a hypodermic needle 15 which after each use is capable of being readily removed from its associated tip for the sterilizing thereof, such construction enabling the use of needles of various lengths with the same or various tips; to provide a 20 construction wherein the needle base is, when assembled, retained in tight frictional contact through a metallic joint connection, insuring a fluid tight joint, and at the same time enabling the mounting to be thoroughly 25 boiled for the sterilizing thereof, without injuring the packing joint; one wherein the needle base is provided with a depression for receiving an outstanding nipple on the mounting, which insures the directing of the 30 hypodermic charge into the needle bore.

With the above mentioned and other objects in view, the invention consists in the novel construction and combination of parts hereinafter described, illustrated in the accompanying drawings and pointed out in the 35 claims hereto appended; it being understood that various changes in the form, proportion, size and minor details of construction within the scope of the claims may be 40 resorted to without departing from the spirit or sacrificing any of the advantages of the invention.

To more fully comprehend the invention, reference is directed to the accompanying 45 drawings, wherein:—

Figure 1 is a view in side elevation of a portion of a hypodermic syringe barrel illustrating the preferred embodiment of our invention applied thereto.

50 Fig. 2 is a longitudinal central sectional view of our invention illustrating the preferred joint connection.

Referring more particularly to the drawings, wherein like characters of reference 55 designate corresponding parts, 1 indicates a

syringe barrel to the threaded discharge end of which is detachably secured the coupling or applicator 2, to which is, in turn, detachably secured the needle tip 3 within which is 60 removably positioned the needle 4, although it will be readily apparent that the end of the syringe might, in some cases, be fashioned to receive the needle and tip, thus dispensing with the applicator in certain cases. The applicator is formed at one end of the 65 tubular channel 5 extending centrally therethrough with a threaded cup or depression 6 for the reception of the outer threaded end 7 of the syringe barrel 1. The base of the depression 6 is provided at a point slightly 70 removed from the side wall of said base with an annular packing receiving groove 8 surrounding the inlet end of the channel 5 and providing an outstanding portion 9 surrounding the inlet end of said channel 5. 75

Within the groove 8 is positioned the metallic packing 10, preferably of tin, and the outer surface thereof lies preferably below the outer end of the outstanding portion 9. With this packing is adapted to contact the 80 terminal discharge end of the syringe barrel when the applicator is attached thereto.

The opposite or outer end of the applicator is also provided with a depression 11, the wall of which is threaded for a portion 85 of its depth and within the base of said depression is the centrally disposed outwardly extending nipple 12, reduced in diameter at its outer end as at 12', forming the discharge end of the channel 5 and surrounding the 90 base of which is the metallic packing 13 preferably of tin, seated in a groove 11' formed in the base of the depression 11, the surface of said packing lying below the outer end of said nipple and the base of said depression 11. 95

Receivable within the depression 11 and having threaded connection with the wall surface thereof, is the inner threaded end of the tip 3, said tip being preferably tapered toward its outer end and provided with a needle receiving bore 14 extending longitudinally through the center thereof. The inner end of the bore 14 is provided with a cylindrical recess 14' for the reception of a 105 cylindrical base 15 which mounts the needle 4, said base being of a length to project slightly beyond the inner end of the tip so that its inner end will rest on the metallic packing 13 with the end of the nipple 110

12 extending into the enlarged stepped seat 16 in the cylindrical base 15, during such time as the tip is mounted in the applicator. The inner end of the needle 4 abuts 5 against a shoulder 4' surrounding the passage in the base 15 which prevents the driving of the needle through the base when the point thereof is driven into the bone tissue.

In our present construction it will be apparent 10 that the needle 4 and base 15 are readily removable from the tip on the separating of the tip from its associated mounting, and it will be observed that the needle is not retained within the tip through any 15 type of frictional joint but the fluid tight connection is made solely between the inner surface of the base 15 mounting the needle and the metallic packing 13 surrounding the nipple 12. It will also be apparent that all 20 packings are metallic and preferably of non-corrosive material which enables the respective elements to be easily and quickly sterilized after use without injuring the packings.

25 As illustrated in dotted lines—Fig. 2, it is apparent that the tips 3 may be of various lengths to correspond to needles of various lengths so as to support the needle adjacent to its end and in practice it is desirable 30 to supply various length tips for use with various lengths and diameters of needles.

Having thus described our invention, what we claim as new and desire to protect by 35 Letters Patent is:—

1. In a hypodermic syringe, a tubular needle tip provided with a needle receiving bore extending therethrough, said tip provided in its base with a cylindrical 40 needle base receiving recess surrounding the inner end of said needle receiving bore, a hypodermic needle for reception within said bore and provided with a centrally channeled base for reception within said receiving recess, said base being of a length 45 to project beyond the inner end of said tip, a channeled member provided with a recess for receiving the inner end of said tip and needle base and to which said tip is detach-

ably secured, and a metallic packing within 50 said recess and into contact with which said needle base is forced to provide a fluid tight joint between the member and needle base.

2. In a hypodermic syringe, a tubular needle tip provided with a needle receiving bore extending therethrough, a hypodermic needle for reception within said bore and provided at its rear end with an enlarged base for contacting with the inner end of 55 said tip, a channeled member provided with a nipple and to which said tip is detachably secured through a threaded connection, said needle base provided with a recess for receiving said nipple end, and a metallic washer carried by said member and surrounding said nipple below the end thereof and with which the portion of said needle base surrounding said recess therein contacts to provide a fluid tight joint between 60 said parts.

3. In combination with a hypodermic syringe including a tubular tip provided at one end with an enlarged recess surrounding the tubular portion thereof, a hypodermic needle for removable reception therein, a 75 tubular base mounting said needle and provided with a flange against which the inner end of the needle abuts, said base adapted for reception within said enlarged recess, and means for uniting said syringe and tip. 80

4. A hypodermic needle including a tubular needle, a tubular base within which the inner end of said needle is received, said base being provided with a shoulder against which the inner end of said needle abuts, 85 whereby the forcing of the needle through the tubular base is precluded on pressure being applied longitudinally thereto.

In testimony whereof we have signed our names to this specification in the presence 90 of two subscribing witnesses.
